OSWALD S. PULLIAM, OF NEW YORK, N. Y., ASSIGNOR TO HIBBARD PROCESS CORPORATION, OF NEW YORK, N. Y., A CORPORATION OF NEW JERSEY.

METAL-WORKING FURNACE

Application filed February 3, 1922. Serial No. 383,958.

To all whom it may concern:

Be it known that I, OSWALD S. PULLIAM, a citizen of the United States, and a resident of the city of New York, borough of Manhattan, in the county and State of New York, have invented new and Improved Metal-Working Furnaces, of which the following is a full, clear, and exact description.

The present invention relates to new and useful improvements in metal working furnaces, and it pertains more particularly to a furnace employed in the manufacture of wrought iron.

It is one of the objects of the present invention to provide a single furnace in which a large batch of molten metal may be treated.

It is a further object of the invention to provide means for intimately mixing the molten metal with slag employed in the process during one of the steps thereof.

In the manufacture of wrought iron, one of the steps of the process is the balling of the metal after the same has reached a certain stage. This balling operation is generally done in a single ball, and it is a further object of the invention to so construct a furnace that a plurality of balls may be manipulated at a single operation.

It is a further object of the invention to construct a furnace in such a manner that the mixing and balling steps are carried out within the same heating chamber.

It is a still further object of the invention to so construct the furnace that it is capable of oscillation and rotation in order that after the batch has reached the proper stage, it may be transferred from one portion of the furnace to the other to carry out the succeeding steps of the operation.

It is a still further object of the invention to so construct a furnace that during the balling process of a plurality of balls, any one of the balls may be selectively discharged from the furnace at the will of the operator.

With the above and other objects in view, reference is had to the accompanying drawings, in which—

50 Figure 1 is a vertical sectional view of a furnace constructed in accordance with the present invention;

Fig. 2 is a detail sectional perspective view of the interior of the furnace.

55 Referring more particularly to the draw-

ings, the reference character 5 designates vertical standards, the upper end of each of which is provided with a bearing 6. The reference character 7 designates the furnace which is formed of any material, such as sheet metal indicated at 8, and lined with a refractory material 9.

Secured to the outer shell of the furnace are trunnions 10, and said trunnions 10 are mounted in the bearing 6 of the standards 5. One of the trunnions is provided with a driving gear 11, which is adapted to be operated by any suitable driving mechanism (not shown). The other trunnion is hollow as indicated by the reference character 12 and is lined with refractory material 9 similar to the body of the furnace, and this hollow trunnion forms the means by which heat is introduced into the interior of the furnace 7.

In constructing the furnace approximately one-half of the inner portion thereof is formed with longitudinally extending inwardly projecting walls 15, and said inwardly projecting walls 15 are adapted to form projecting ridges over which the material is precipitated during its mixing with mill scale, slag, or the like. The remainder of the interior of the wall of the furnace is formed with a plurality of circumferentially extending projections or ribs 16. These circumferentially extending projections or ribs 16 are formed by interposing courses 17 of fire-brick with respect to courses 18 of fire-brick, the courses 18 having concave surfaces and being spaced with respect to one another by the heretofore mentioned courses 17.

The outer shell 8 of the furnace is provided with a plurality of separate doors 20, and said doors are so positioned that they form a part of the channels between the projections or ribs 16 in such a manner that the material contained in any of said channels may be discharged therefrom independently of the remaining channels.

The operation of the device is as follows:

With the furnace positioned as shown in Fig. 1, one of the doors 20 is opened and the charge to be treated is introduced therethrough to the space between the projections or ribs 15. After the charge has been thus positioned within the furnace, the furnace is oscillated and the charge is precipitated backwardly and forwardly on the central

105

110

ribs 15 to thoroughly mix the elements of the charge.

When the charge attains the proper condition, the furnace is rotated in such a manner that the ribs or projections 16 are brought to the bottom thereof. In thus rotating the furnace the charge is transferred from the space between the projections or ribs 15 to the channels between the projections or ribs 16, and said charge will be divided into four parts, there being one part in each of the channels. With the several parts in this position, the furnace is again oscillated and the charges in the channels between the projections or ribs 16 are balled.

As the balling operation is carried out, the several balls owing to their nature, will not all be ready to be discharged at one time. However, by the provision of the several doors 20, as any of the balls reaches the condition to be discharged from the furnace, this may be accomplished by opening the door 20 of the channel in which said ball is contained.

From the foregoing it is apparent that the present invention provides a new and improved form of puddling and balling furnace in which a plurality of balls may be simultaneously handled and singly and independently discharged from the furnace at any time during the process.

What is claimed is:

1. In a metal balling furnace, means for forming a plurality of individual balls, and means for selectively discharging said balls from the furnace.

2. In a puddling and balling furnace,

means for mixing a single batch of molten metal, means for dividing said mixed batch 40 into a plurality of balls, and means for selectively discharging said balls.

3. In a puddling and balling furnace, means for operating upon a single batch, means for dividing said batch into a plurality of separate batches, means for simultaneously balling said separate batches, and means for selectively discharging said separate batches.

4. In a furnace for puddling and balling 50 iron, a plurality of ribs extending parallel with the longitudinal axis of the furnace, said ribs serving to mix a batch of molten metal, and a plurality of ribs extending circumferentially of the furnace to provide 55 a plurality of intermediate channels adapted to divide the batch into a plurality of individual batches, as and for the purpose set forth.

5. A metal working furnace formed with 60 a plurality of working surfaces, means within one of said working surfaces for mixing a batch of molten metal, means within the other of said working surfaces for dividing said batch into a plurality of separate 65 batches and subsequently balling said separate batches, and means for selectively discharging the several batches after they have been subjected to the balling operation.

6. In a metal working furnace, a plurality 70 of parallel channels for forming a plurality of individual balls and means associated with said channels whereby the balls therein may be discharged therefrom.

OSWALD S. PULLIAM.
